UNITED STATES PATENT OFFICE.

BURR H. CALDWELL, OF NIAGARA FALLS, NEW YORK, ASSIGNOR TO U. S. LIGHT & HEAT CORPORATION, OF NIAGARA FALLS, NEW YORK, A CORPORATION OF NEW YORK.

PLATE-SUPPORTING MEANS.

Application filed September 24, 1917, Serial No. 192,880. Renewed June 24, 1922. Serial No. 570,719.

The present invention relates to plate supporting means.

In large storage batteries, as for instance, those used in marine service, it is necessary 5 to provide special means for supporting the storage battery plates. In lifting the plates out of the cells for the purpose of inspection, or for any other purpose, it is common practice to do such lifting by means of the 10 cell posts. It is common practice to provide four cell posts for each cell and the lifting is done on all four posts, whereby to reduce the stresses on the plates to a minimum. As the plates are lifted out of the cell by the cell 15 posts, the plates of one polarity tend to swing away from the plates of the other polarity. To overcome this tendency, it has been common practice to bandage the plates together after they are drawn part way out 20 of the cell.

The present invention has for one of its objects the provision of plate-supporting means whereby the plates may be securely supported from the walls of the cell.

25 A further object is to provide plate-supporting means which will co-operate with the plates in such a way that when the plates are lifted from the cell, said plates will be locked together, whereby the tendency of the plates to swing apart will be effectually resisted.

30 A further object is to provide a construction in which treeing across from plates of one polarity to plates of the opposite polarity will be minimized.

35 Referring to the drawings—

Figure 1 is a sectional view illustrating one embodiment of the present invention.

40 Figure 2 represents on a larger scale a plate-supporting member according to the present invention.

The walls of a battery cell are indicated by the numeral 1. A number of plates in said cell of opposite polarities are indicated 45 respectively by the numerals 2 and 3. Straps 4 connect all of the plates 2, which are of one polarity, while straps 5 connect all of the plates 3 which are of the opposite polarity. As stated above, it is common practice to provide a pair of cell posts for each of the straps 4 and 5, which cell posts will be placed adjacent to the opposite ends of each strap. Each of the plates 2 and 3 50 may be of the same configuration and is pro-

vided with a side lug 6. Each of the plates 55 is also provided with a side lug 7 which, as will be noted in Fig. 1, is located at a point higher on the plate than the lug 6 and on the opposite edge of the plate from the lug 6. Each of the walls 1, 1, of the cell is provided with a shoulder 8 adapted to support the lugs 6, 6. Each of said shoulders 8, 8, also supports a supporting member 9 which is of comb-shaped formation. The teeth 10 of said member 9 are adapted to straddle 60 the lugs 6 of the plates 2 and 3. The lugs 7 of the plates 2 and 3 are adapted to rest upon the top of a member 9. By this construction the lugs 6 of each plate will be supported on the one side by a shoulder 8 and 65 on the other side the lugs 7 will be supported by the member 9 which in turn is supported by a shoulder 8. The space between the lugs 6 of the plates of one polarity and the lugs 7 of the plates of opposite polarity 70 should be sufficient to receive the transverse portion of the member 9 lying above the space between the teeth 10. Said transverse portion of the member 9 should fit loosely 75 between adjacent lugs 6 and 7, when the 80 plates are in position in the jar. When it is desired to lift the plates out of the cell by the terminal posts, said members 9 will effectually lock the plates against turning movement relative to one another, whereby 85 no bandaging of the groups will be necessary.

It will be noted that the adjacent sides of plates of opposite polarity are supported at different levels, whereby should any deposit 90 form either on the shoulders 8 or upon the members 9, said deposit cannot possibly form a short circuit between plates of opposite polarity.

According to the present invention a very 95 sturdy construction is provided which is cheap to manufacture, in which short-circuiting is minimized and in which handling is accordingly facilitated.

It will be noted from the drawings that 100 the cross-section of that portion of the member 9 above the space between the teeth 10 is a parallelogram having other than right angles. It will be clear that any other angular relation may be provided if desired. 105

The described embodiment of the present invention is chosen merely for the purpose of illustration and is not to be considered in

a limiting sense. Many modifications may be made therein. It is desired that the patent shall cover all such modifications that come within the scope of the invention as defined by the appended claims.

What I claim as new and desire to secure by Letters Patent of the United States, is—

1. In a battery cell, a jar having shoulders on opposite walls, plates each having lugs on opposite edges thereof, certain of said lugs being adapted to rest directly on certain of said shoulders, and supporting means on each of said shoulders upon which other of said lugs are adapted to directly rest.
2. In a battery cell, a jar provided with means for supporting battery plates from the side walls, plates in said cell, each of said plates having side lugs, the lugs on adjacent sides of alternate plates being spaced apart vertically, and a plurality of comb-shaped members each having its teeth resting upon said first mentioned means, the transversely extending portion of each of said comb-shaped members lying between said spaced apart lugs.

3. In a battery cell, groups of plates of opposite polarities, transversely extending means extending through said groups and adapted to abut against opposite parts of said plates to prevent swinging movement of said plates, and a jar for said groups, said jar being provided with transverse means for directly supporting portions of said plates and said transversely extending means, said transversely extending means being adapted to directly support other portions of said plates.

4. A battery cell having a side wall provided with a shoulder, battery plates having their edges adjacent to said side wall, alternate plates having lugs adapted to rest upon said shoulder, a comb-shaped member having teeth resting upon said shoulder and straddling said lugs, the remainder of said plates having lugs adapted to rest upon the transverse portion of said comb-shaped member.

In witness whereof, I have hereunto subscribed my name.

BURR H. CALDWELL.
